UNITED STATES PATENT OFFICE.

THEODOR H. J. LECKBAND, OF ADAIR, IOWA, ASSIGNOR TO THE LECKBAND GENERATOR COMPANY, OF DES MOINES, IOWA.

ACETYLENE-GAS GENERATOR.

SPECIFICATION forming part of Letters Patent No. 665,019, dated January 1, 1901.

Application filed June 6, 1898. Renewed November 23, 1900. Serial No. 37,458. (No model.)

To all whom it may concern:

Be it known that I, THEODOR H. J. LECKBAND, a citizen of the United States, residing at Adair, in the county of Adair and State of Iowa, have invented a new and useful Acetylene-Gas Generator, of which the following is a specification.

My object is to provide a simple, strong, durable, and efficient apparatus for generating acetylene gas in which the following novel features are greatly advantageous: first, improved means for water-sealing in a retort a plurality of pans adapted to contain calcium carbid in such a manner that water will be admitted to flow from one pan to the adjacent pan as required to exhaust the charge of the carbid in the pans successively and to facilitate cleansing and refilling the pans with carbid; second, pivotally and detachably connecting the retort with a water-tank and also pivotally and detachably connecting the retort with water-pipes and gas-conveying tubes fixed to the water-tank; third, providing a water-tank with a conical bottom to strengthen it, and to provide a chamber under the tank and a water-trap in the chamber for catching drip-water, and water-sealing gas-tubes and water-pipes connected with the retort, the water-tank, and the gas-holder; fourth, providing an open basin on the outside of the water-tank and connecting it with the retort in such a manner that water in the basin will coact with gas in the gas-holder in regulating the flow of water to the carbid in the retort, and, fifth, providing improved means for arresting the flow of water to the retort while gas continues to flow to burners and as required to open the retort to refill the pans with carbid.

My invention consists in the construction, arrangement, and combination of elements, as hereinafter set forth, pointed out in my claims, and illustrated in the accompanying drawings, in which—

Figure 1 is a side view of the complete portable generator adapted to be connected with gas-distributing tubes and burners in a building as required for practical use. Fig. 2 is a vertical central sectional view of the water-tank, water-basin, water-trap, and the gas-tubes and water-pipes connected as required

to coact with each other and also coact with the water-pipes and gas-tubes on the outside of the water-tank. Fig. 3 is an enlarged vertical central sectional view of the retort, 55 showing the manner of forming and combining a plurality of pans adapted to retain calcium carbid and water. Fig. 4 is an enlarged top view of one of the pans removed from the retort. Fig. 5 is an enlarged transverse 60 sectional view on the line $x-x$ in Fig. 1, showing the swinging bracket that supports and carries the retort and the relative positions of the water-pipes and gas-tubes connected with the water-trap under the elevated fixed 65 bottom of the tank. Fig. 6 is an enlarged transverse sectional view on the line $y-y$ in Fig. 1, showing the positions of the water-pipes and gas-tubes relative to each other and the water-tank and water-basin. 70

The letter A designates a water-tank that has an open top and a conical fixed bottom A² and a downward extension A³ to produce an enlarged base and a chamber under the fixed bottom.

A⁴ is an open-topped annular basin fixed around the outside and top portion of the tank A.

B is an open-topped double-walled vessel and portion of the retort.

B² is the inner wall fixed to the bottom of the vessel in concentric position with the outer wall.

B³ is an open-ended cylinder telescopically and revolvably connected with the double-walled vessel and provided with a fixed airtight top B⁴ and handholds B⁵ thereon to facilitate handling the cylinder. An open-ended screw-threaded tube B⁶ is fixed in the center of the top B⁴ by means of nuts or screw-seats fixed to the top, as shown in Fig. 3, or in any suitable way so that the cylinder and tube can be jointly rotated as required in connecting the retort with a T-pipe coupling B⁷ and as required to open the generator and to 90 empty dregs from the pans therein and refill them with carbid.

C is a pan that has a larger diameter at its top than at its bottom and is provided with a plurality of vents d near its top circumference to allow water to flow outward into a pan in a lower plane. d' represents wires fixed in

parallel position across the top to support a pan. A plurality of pans C are thus provided to be placed removably and interchangeably within the double-walled vessel B, as shown 5 in Fig. 3, to be filled with calcium carbid whenever desired.

C² is a water-trap in the chamber under the tank A.

C³ is an open-bottomed gas-holder telescopically connected with the water-tank A.

C⁴ is an open-bottomed tube fixed to the top and center of the gas-holder C³.

f is a gas-tube telescopically connected with the lower open end of the fixed tube C⁴.

15 f' is a T-coupling connected with the lower end of the tube f and the top of the water-trap C².

20 f'' is a tube connected with the coupling f' and passes outside of the water-tank to be extended outside of a building to carry off any surplus of gas that may gather in the gas-holder to produce undue pressure.

25 f''' is a T-coupling at the top portion of the tube C⁴, and f'''' is a safety-tube connected with said coupling to extend downward into water in the tank A in such a manner that it will be water-sealed at all times excepting when undue pressure of gas in the gas-holder C³ lifts said holder and elevates the lower end 30 of said safety-tube above the water-line in the tank A. It is obvious that whenever a surplus quantity is admitted into the gas-holder it will be thus automatically relieved therefrom as required to prevent undue pressure and to assure safety in the operation of 35 my invention.

g is an open-topped water-pipe on the outside of the gas-holder C³ and telescopically connected with an open-topped water-pipe g', 40 fixed to the outside of the tank A by means of a sheet-metal cover g'', soldered thereto or in any suitable way.

45 g''' is a pipe connected with the pipe g and the basin A⁴ by means of a flexible tube g'''' in such a manner that water can flow from the basin into the pipe g and the gas-holder C³ allowed to ascend and descend.

50 g'''' is a pipe connected with the lower end of the pipe g' and the T-coupling B⁷ in such a manner that water will be conveyed thereby from the pipe g' to the retort as required to conduct water from the basin A⁴ into the upper pan C whenever the supply of gas in the gas-holder is reduced sufficiently to allow 55 the pipe g to be lowered so as to bring the top of the pipe g'''' below the level of water in the basin A⁴ and to start the generation of gas in the retort by wetting the carbide confined therein. The open-topped pipe g will always 60 remain water-sealed at its lower end, and the air that enters its open top will aid in pressing water from the pipe g' into the retort.

65 h is an arched gas-tube connected with the retort by means of the tube B⁶ and the coupling B⁷ and extended into the tank A and connected with the lower end of a tube h', that is fixed to the trap C² by means of a T-coupling h''.

h''' is a tube fixed to said coupling and extended into the trap and bent double at its lower end portion to increase in length, 70 so as to retain a sufficient quantity of water to resist gas-pressure downward in the tube h' and to discharge water from the pipe h that may be conveyed thereby.

h'''' is a screen connected with a tube i, 75 that extends downward from the top of the tube h' in such a manner that the screen will be submerged in the water in the tank and gas filtered therethrough, so as to be cooled in the water before it ascends through the 80 water into the gas-holder C³, and the tube water-sealed at all times when the retort is disconnected from the tube h, so that no gas whatever can return from the gas-holder into the tubes i and h to escape.

J is a sleeve on the pipe h, and J² is a bracket fixed to the lower end of the sleeve to rotate therewith and to support and carry the retort that is designed to be placed thereon, as shown in Fig. 1.

90 k is a gas-tube fixed to the bottom A² of the tank A and extended up into the gas-holder C³ and downward below said bottom and connected with the top of the trap C² by means of T-coupling k''. k''' is a tube that 95 extends from said coupling through the wall of the chamber and is designed to be connected with burners in a building.

k'''' is a tube extended from the coupling k'' into the trap C² to water-seal the tube k 100 to receive any water of condensation in the tube x.

105 m is a prop hinged to the basin A⁴ in such a manner that its free end can be turned downward, as shown in Fig. 1, and also turned upward to engage the T-coupling on the pipe g as required to retain the pipe g''' elevated and the flow of water discontinued through the tubes g''', g'', g', and g'''' to the retort, while the retort is opened by rotating the part B⁴, 110 (the bell of the generator,) so that the parts can be separated as required to clean and refill the pans C with carbide.

115 n is an elbow-shaped tube fixed in the top of the trap C² and extended out through the wall A³ of the chamber under the tank A to carry off any surplus of water that may collect in the trap.

120 The tubes h', f', and k are fixed to the bottom A² of the tank by means of nuts r and r', 120 soldered thereto or in any suitable way so as to produce water-tight joints.

125 s is a vent in the top portion of the tank A, that will allow surplus water to flow from the tank into the basin A⁴ whenever necessary.

130 It is obvious that when there is a sufficient quantity of gas stored in the gas-holder to elevate it and the pipes g and g'', carried therewith, above the water in the tank the flow of water from the basin A⁴ to the retort will be automatically cut off and the wetting of carbide and generating of gas stopped, and, vice versa, when the gas-supply is suf-

ficiently diminished in the gas-holder it will descend and lower the pipes g and g'' , so that water will be again automatically turned on to flow from the basin A^4 through the pipes that connect the basin with the retort as required to wet the carbid and start the generation of gas again. By the alternate pressure of water and gas the flow of water and generation of gas are automatically regulated. It is also obvious that when enough water has been admitted into the upper pan C to exhaust all of the carbid therein and the flow of water through the pipes g''', g''', g', g' , and g'''' continued from the basin A^4 to the retort the water admitted into the upper pan will then overflow therefrom through the vents d into the pan next below it and that thus all the pans will be successively and gradually supplied with water to wet the carbid therein as required to exhaust all the carbid in the retort and to generate gas therefrom continuously for any given time it may be desired to operate the generator.

To clean and refill the pans, revolve the open-bottomed cylinder B^3 as required to lower it in the open-topped and double-walled vessel B to disconnect the screw B^6 from the T-coupling B^7 . Then swing the bracket J^2 to carry the vessel B and its contents from under the coupling B^7 , so that the cylinder B^3 can be lifted out of the vessel to gain access to the pans C , and when the pans are cleaned and refilled with carbid the cylinder can be replaced and the vessel carried back to its place under the coupling, by means of the swinging bracket, and the cylinder B^3 then lifted and rotated as required to connect the fixed tube in its top with the coupling B^7 .

From the foregoing description of the construction and function of each element and subcombination of my invention its operation, utility, and advantages will be obvious to persons familiar with the art to which it pertains.

What I claim, and desire to secure by Letters Patent therefor, is—

1. A retort for making gas comprising a double-walled open-topped vessel, one or more receptacles for calcium carbid placed in the vessel, an open-bottomed revoluble cylinder having a fixed open-ended tube in its top, a fixed pipe for conveying water into said tube and retort and conveying gas from the retort, and a screw-coupling for connecting said tube and pipe arranged and combined to operate in the manner set forth.

2. In a gas-generator, a water-tank having a basin fixed around the outside of its top and provided with a vent to discharge water into said basin, a gas-holder telescopically connected with the tank, telescopic tubes connected with the bottom of the tank and the top of the gas-holder, a tube connected with the lower end of said telescopic tube and also connected with a retort, a telescopic pipe connected with the outside of the tank and

extended up on the outside of the gas-holder, a flexible tube connected with the said water-basin on the outside of the tank and also connected with said telescopic water-pipe, all arranged and combined to operate in the manner set forth for the purposes stated.

3. In a gas-generator, a water-tank having a basin fixed around the outside of its top and provided with a vent to discharge water into said basin, a gas-holder telescopically connected with the tank, telescopic tubes connected with the bottom of the tank and the top of the gas-holder, a tube connected with the lower end of said telescopic tube and extended to the outside of the tank, a telescopic pipe connected with the outside of the tank and extended up on the outside of the gas-holder, a flexible tube connected with the said water-basin on the outside of the tank and also connected with said telescopic water-pipe, and a retort connected with the telescopic water-pipe, all arranged and combined to operate in the manner set forth for the purposes stated.

4. In a gas-generator, a water-tank having a basin fixed around the outside of its top and provided with a vent to discharge water into said basin, a gas-holder telescopically connected with the tank, telescopic tubes connected with the bottom of the tank and the top of the gas-holder, a tube connected with the lower end of said telescopic tube and extended to the outside of the tank, a telescopic pipe connected with the outside of the tank and extended up on the outside of the gas-holder, a flexible tube connected with the said water-basin on the outside of the tank and also connected with said telescopic water-pipe, and a retort connected with the said telescopic water-pipe and means connected with said telescopic water-pipe to support the gas-holder in an elevated position, all arranged and combined to operate in the manner set forth for the purposes stated.

5. In a gas-generator, a water-tank having a basin fixed around the outside of its top and provided with a vent to discharge water into said basin, a gas-holder telescopically connected with the tank, telescopic tubes connected with the bottom of the tank and the top of the gas-holder, a tube connected with the lower end of said telescopic tube and extended outside of the tank, a telescopic pipe connected with the outside of the tank and extended up on the outside of the gas-holder, a flexible tube connected with the said water-basin on the outside of the tank and also connected with said telescopic water-pipe, and a retort connected with the said telescopic water-pipe and means connected with said telescopic water-pipe to support the upper portion of the said telescopic pipe in an elevated position, and a tube connected with the retort to convey gas from the retort into the gas-holder, all arranged and combined to operate in the manner set forth for the purposes stated.

6. In a gas-generator, a water-tank having a basin fixed around the outside of its top and provided with a vent to discharge water into said basin, a gas-holder telescopically connected with the tank, telescopic tubes connected with the bottom of the tank and the top of the gas-holder, a tube connected with the lower end of said telescopic tube and extended outside of the tank, a telescopic pipe connected with the outside of the tank and extended up on the outside of the gas-holder, a flexible tube connected with the said water-basin on the outside of the tank and also connected with said telescopic water-pipe, and a retort connected with the lower end of said telescopic water-pipe and means connected with said telescopic water-pipe to support the gas-holder in an elevated position, and a tube connected with the retort to convey gas from the retort into the gas-holder, all arranged and combined to operate in the manner set forth for the purposes stated.

7. The double-walled vessel B, the cylinder B³ having a fixed top, fixed handholds B⁵ and a fixed tube B⁶, in combination with the coupling B⁷, the pipe g^{""} and the tube h, and the swinging bracket J² pivotally connected with a water-tank, as and for the purposes stated.

8. An acetylene-gas generator comprising a water-tank having a chamber under its bottom, a water-trap in said chamber, and a water-basin at its top and outside and a vent

communicating with said basin, a gas-holder telescopically connected with the tank, a telescopic water-pipe fixed to the tank and extended up outside of the gas-holder, a flexible tube connected with said water-basin and said telescopic pipe, a retort connected with said telescopic pipe, a telescopic gas-tube fixed to the bottom of the tank and to the top of the gas-holder and connected with the said trap and provided with a tube extending downward from its top portion and a tube extending outward from its lower end, a tube fixed to the bottom of the tank and connected with said trap and said retort to convey gas into the gas-holder, a tube fixed to the bottom of the tank and connected with said trap and extended outside of the tank to convey gas to burners, a bracket pivotally connected with the telescopic water-pipe fixed to the outside of the tank and the gas-holder for supporting and carrying the retort and means for detachably connecting the retort with the pipe that conveys water from the water-basin to the retort and gas from the retort to the gas-holder, all arranged and combined to operate in the manner set forth for the purposes stated.
